JACK FOR REMOVING CYLINDER HEADS
FROM BUS TYPE ENGINES

Aloysius P. Braun, Denver, Colo., assignor of one-half to George R. Fabrizio, Denver, Colo.

Application July 17, 1948, Serial No. 39,317

4 Claims. (Cl. 214—149)

1

This invention relates to an attachment for garage and shop jacks. In certain types of buses and trucks a horizontal engine is employed, the cylinders of which lie in a horizontal plane below the floor of the bus. The side walls of the bus body project downwardly below and beyond the sides of the engine. It is practically impossible with an ordinary garage jack to remove the cylinder head from the engine and withdraw it from beneath the body of the bus, for in order to pass beneath the sides of the body, the cylinder head must be turned from its horizontal position to a vertical position.

The principal object of this invention is to provide a simple and highly efficient attachment which can be placed upon any of the standard jacks, and which can be attached to the cylinder head and its accessories while the latter is on the engine, so that the head may be lifted and moved sidewardly to release it from the engine block studs, then lowered to pass it beneath the sides of the bus body.

Another object is to so construct the device that during the lowering operation the head will be automatically turned from its natural horizontal position to a vertical position to allow it to clear the bus sides while being removed, and to place it in a convenient position to be worked upon.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawings:

Fig. 1 is a perspective view of the improved jack attachment;

Fig. 2 is a plan view thereof, illustrating the attachment in place on one form of conventional shop jack;

Fig. 3 is a side view thereof, illustrating it in the lowered position on a conventional jack; and

Fig. 4 is a similar view, illustrating the jack in the elevated position.

In Fig. 4 a conventional horizontal cylinder head is indicated at 29, and the portion of the cylinder block to which the head is normally attached is indicated in broken line at 30. The usual accessories which form a part of the assembled head are designated by numerals as follows: intake manifold 31, exhaust manifold 32, 33

2

valve rockers 33, and spark plugs 34. The position of the lower edge of the body of a conventional bus is indicated at 38.

In the drawing, one type of a conventional garage jack is indicated at 10 mounted on caster wheels 11. Jacks of this type are provided with projecting shaft studs 36 and with a seat or platform 12, which is elevated on lifting arms 13 actuated from a ratchet crank 14. Other jacks upon the market are operated hydraulically to lift the platform 12 by a pumping action on a handle. The jack construction forms no part of the present invention. This attachment is applicable to any of these conventional jacks, and the jack illustrated is simply for the purpose of showing the attachment and the operation thereof.

The improved attachment is illustrated in Fig. 1 and comprises a base plate 15 provided with bolt holes 16 for the reception of attachment bolts 17, 20 by means of which the plate 15 may be secured to the jack platform 12.

A structural steel channel 18 is mounted on a hinge 19 welded or otherwise secured to the upper face of the base plate 15. The hinge 19 is placed substantially in the middle of the channel 18 so that the latter will project outwardly at both sides of the plate 15. The hinge is positioned at the back of the channel 18 so that the open face of the latter will face forwardly when upright, and upwardly when folded down onto the plate 15.

The mid-portion of the channel 18 is cut away, as shown at 20, to provide clearance for engine head accessories. A bracket ear 21 projects rearwardly from the upper portion of the channel at each side of the cut-away 20, and a brace bar 22 is hingedly mounted on each ear 21 by means of a hinge bolt 23.

Two attachment arms 24 are secured to the upper flange of the channel 18 by means of suitable attachment bolts 25. The arms project forwardly and upwardly from the channel and terminate in attachment plates 26 containing bolt holes 27. Two angle iron posts 28 are welded to the lower flange of the channel 18 and project forwardly therefrom.

The attachment is applied to the jack by bolting the base plate 15 to the platform 12 by means of the bolts 17. The brace bars 22 are provided with holes 35. These holes are slipped over the extremities of the shaft studs 36, and the device is ready for use.

To remove the cylinder head 29, the jack is wheeled beneath the bus and the handle 14 is operated to bring the channel 18 immediately below

and against the exhaust manifold 32. The two attachment arms 24 are now swung to position the attachment plates 26 over the carburetor attachment flanges of the intake manifold 31, to which they are bolted through the holes 27 by means of attachment bolts 37.

It will be noted that the angle posts 28 rest against the cylinder head 29 to support the latter. The cylinder head nuts are now removed and the jack 10 is backed away from the cylinder block 30 to remove the head therefrom.

The jack platform is now lowered to the position of Fig. 3. As the platform descends, the reaction of the rigid brace bars 22 will prevent the rear edge of the channel 18 from descending, and will lower the forward edge thereof so as to swing the channel to the position of Fig. 3, with the cylinder head in the vertical position. This lowers the head sufficiently to allow the jack to be wheeled from beneath the sides 38 of the bus body. It will be noted that in the lowered position the weight of the head 29 and its attachments is supported by the two attachment arms 24.

When it is desired to replace the head, the process is simply reversed, and as the platform 12 rises, the head will turn from the vertical to the horizontal position so that it may be easily and accurately returned to the cylinder block 30.

Certain types of bus bodies have been encountered in which the sides 38 are so low that the platform 12 cannot be elevated to the full height of Fig. 4. To adapt the attachment for this type of bus body, freely swinging hook members 39 are provided, suspended from attachment ears 40 on the channel 18. Two holes 41 are drilled in the jack below the hook members 39 to receive the lower hooked extremities thereof. When using the hook members, the brace bars 22 are disconnected from their shaft studs 36. The hook members replace the brace bars and function similarly to the latter. It will be noted, however, that since the hook members are much shorter than the brace rods, the channel 18 will tilt much more rapidly as it is lowered to the position of Fig. 3.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. An attachment for handling an automotive cylinder head of the bus type from a floor jack having an elevating platform, comprising: a base plate adapted to be attached to said platform; a hinge extending transversally of the upper face of said base plate; a head-engaging member hinged at its one side to said hinge and extending laterally outward beyond both sides of said base plate; means for attaching said engaging member to a cylinder head; brace bars hingedly secured to the other side of said engaging member distant from said hinge; means for attaching the free extremities of said brace bars to said jack so that they will exert a rotative movement on said engaging member as the latter moves vertically with said platform; attachment arms attached to said engaging member; and means for attaching said attachment arms to said cylinder head.

2. An attachment for handling an automotive cylinder head of the bus type from a floor jack having an elevating platform, comprising: a

base plate adapted to be attached to said platform; a hinge extending transversally of the upper face of said base plate; a head-engaging member hinged at its one side to said hinge and extending laterally outward beyond both sides of said base plate; means for attaching said engaging member to a cylinder head; brace bars hingedly secured to the other side of said engaging member distant from said hinge; means for attaching the free extremities of said brace bars to said jack so that they will exert a rotative movement on said engaging member as the latter moves vertically with said platform; attachment arms attached to said engaging member; means for attaching said attachment arms to said cylinder head; and posts secured to said engaging member and extending outwardly therefrom so as to be horizontal when said platform is lowered, and vertical when said platform is elevated, said posts being adapted to engage and support said cylinder head.

3. Means for handling a cylinder head having an intake and an exhaust manifold attached thereto from a floor jack having an elevating platform, comprising: a base plate secured on said platform; a hinge extending transversally of the upper face of said base plate; a channel member extending laterally across the base plate, said channel member being mounted on said hinge so that its open side will project forwardly therefrom; attachment ears projecting rearwardly from the back of said channel member adjacent the side distant from said hinge; a brace bar extending from each of said ears; and means for attaching said brace bar to said jack, said brace bars having a length sufficient to swing said channel member from a horizontal to a vertical position as said platform is lowered from its upper to its lower position.

4. Means for handling a cylinder head having an intake and an exhaust manifold attached thereto from a floor jack having an elevating platform, comprising: a base plate secured on said platform; a hinge extending transversally of the upper face of said base plate; a channel member extending laterally across the base plate, said channel member being mounted on said hinge so that its open side will project forwardly therefrom; attachment ears projecting rearwardly from the back of said channel member adjacent the side distant from said hinge; a brace bar extending from each of said ears; means for attaching said brace bar to said jack, said brace bars having a length sufficient to swing said channel member from a horizontal to a vertical position as said platform is lowered from its upper to its lower position; attachment arms secured to said channel; and means on said attachment arms for attaching them to said intake manifold, said channel being adapted to receive said exhaust manifold.
